STEAK KNIFE

Emil S. Polk, Scarsdale, N. Y.

Application February 26, 1954, Serial No. 29,229

Term of patent 14 years

(Cl. D22—3)

Fig. 1

Fig. 2

Fig. 3

Fig. 4

Fig. 5

Figure 1 is a side elevational view of a steak knife embodying my new design.

Figure 2 is a bottom edge view thereof.

Figure 3 is a transverse sectional view as seen from the plane 3—3 on Figure 1.

Figure 4 is a transverse sectional view as seen from the plane 4—4 on Figure 1; and

Figure 5 is a transverse sectional view as seen from the plane 5—5 on Figure 1.

I claim:

The ornamental design for a steak knife, as shown.
